UNITED STATES PATENT OFFICE.

OSCAR SCHIMMEL, OF CHEMNITZ, SAXONY, GERMANY.

SPINNING-MULE.

SPECIFICATION forming part of Letters Patent No. 408,540, dated August 6, 1889.

Application filed January 12, 1889. Serial No. 296,186. (No model.) Patented in France September 6, 1888, No. 192,815, and in Belgium September 6, 1888, No. 83,158.

To all whom it may concern:

Be it known that I, OSCAR SCHIMMEL, a subject of the King of Saxony, residing at Chemnitz, in the Kingdom of Saxony, Germany, 5 have invented new and useful Improvements in the Driving-Gear of Self-Actors, (for which I have obtained Letters Patent in France September 6, 1888, No. 192,815, and in Belgium September 6, 1888, No. 83,158,) whereof the 10 following is a specification.

My invention relates to the driving-gear of the carriages of spinning-mules employed in spinning carded yarn, the said gear comprising a run-out pulley with two portions of different diameters; and the invention consists 15 in features of novelty hereinafter described with reference to the accompanying drawings, and particularly pointed out in the claims.

20 In the annexed drawings, Figure 1 shows in sectional side elevation a rope-pulley of the present construction, together with a part of its driving-gear. Fig. 2 is a front view of the pulley. Fig. 3 is a sectional view of a 25 pulley and its driving-gear carried out according to my invention. Fig. 4 is a sectional side view of a part thereof. Fig. 4^a shows another part in plan. Fig. 5 is a skeleton view of a self-actor provided with the im- 30 proved gear, and Fig. 6 a plan corresponding to Fig. 5.

In self-actors for carded yarn the carriage carrying the spindles is driven during its run out with decreasing speed. During the first 35 part of the said run in which roving is supplied, the carriage is caused to move as fast as possible in order to shorten this period, which is unavailing to the spinning operation proper, whereas during the second part, 40 in which the roving that had been supplied is drawn out and twisted, the carriage moves slowly. These different motions are obtained by means of a pulley, (run-out pulley,) such as the one shown in Figs. 1 and 2 and 45 marked by the letter S. The said pulley has helical grooves, which serve to receive the rope that moves the carriage, and it is composed of a portion L, of large diameter, operating while the roving is supplied or delivered, a portion V of small diameter in operation at the period of drawing out and twisting,

and a spiral which connects the grooves of the said portions together. In order to avoid a breakage of the roving while being drawn out, this operation must be carried out gently 55 by causing the carriage to run very slowly at the time. A considerable difference of diameter of the pulley portions L and V is therefore required, which renders it necessary to make the diameter of the portion L 60 very large and the portion V of such small size that it is hardly possible to pass a shaft of sufficient thickness through the same, the pulleys being for this reason mounted on the ends of shafts reduced in diameter, as shown 65 by Fig. 1. Moreover, it follows from the great difference in the diameters of the pulley portions L and V that the connecting spiral, which, in order to avoid shocks must not be made too steep, will have a length correspond- 70 ing to a considerable portion of the run of the carriage, and this is another source of inconvenience. For the purpose of always keeping the roving-threads between the delivering-rollers and the spindles stretched, 75 the operation of drawing out the said threads should commence, and consequently the stoppage of the delivering-rollers takes place, when the carriage-rope passes over at the point a, Fig. 2, from the pulley portion L 80 to the spiral; but as from the great length of the spiral the speed of the carriage decreases but slowly the drawing out of the threads would in such case ensue too rapidly, so that they would break. For this reason the 85 delivering-rollers are not stopped until the carriage-rope has passed by a certain length on the spiral—say to the point b—the consequence thereof being, however, that the speed of the carriage meanwhile decreases to less 90 than the peripheral speed of the rollers and that the threads become slack, wherefrom an uneven yarn results. For the purpose of obviating these inconveniences I reduce the difference between the diameters of the two por- 95 tions of the rope-pulley by making the larger portion smaller and the smaller portion larger than heretofore, while at the same time I impart to the pulley two different speeds in succession, the speed at which it rotates when 100 the rope runs on the larger pulley portion being by so much greater than in the present

machines as that the usual high speed of the carriage is maintained at the time roving is supplied, whereas the speed of the pulley is comparatively less when the rope runs on the 5 portion of smaller diameter—*i. e.*, at the time the delivering-rollers are at rest and the roving is drawn out and twisted. In consequence of the said reduction of the difference of the diameters of the pulley portions the spiral 10 that connects the said portions together becomes shorter, so that the change from the greater speed of carriage to the lower speed ensues more rapidly, while, nevertheless, this change takes place gently enough, as the slope 15 or angular incline of the spiral is not altered. This mode of driving the pulley presents the additional advantage that different proportions of speeds of the carriage may be obtained with the same pulley by changing the 20 gear-wheels that produce either of the said speeds.

In the improved pulley-driving mechanism shown by Fig. 3 the ordinary driving-gear of the pulley is connected to the roving-delivering 25 roller by a differential wheel-work in such manner that as soon as the said roller is stopped the pulley will rotate more slowly.

Z and Z' are two spur-wheels, such as are now in use in self-actors. As shown by Figs. 30 5 and 6, these wheels are driven from the main shaft A through the medium of the wheels o p q. The wheel Z has fixed to it the change-wheel z, which gears with the wheel R, being the present pulley-driving wheel, (see Fig. 1,) while the wheel Z' is connected by the toothed coupling K' with the shaft C' of the roving-delivering roller C. The wheel R, heretofore directly connected to the pulley-shaft W by the toothed coupling K, as in 35 Fig. 1, is loose on the sleeve g of the latter, while the shaft W carries, loosely rotating thereon, the spur-wheel R', which gears with the pinion r, keyed to the shaft C'.

The two wheels R and R' are provided with 45 the respective bevel-wheel teeth k and k', with which gears the bevel-wheel U, arranged to turn freely on a pin l, fixed radially in the disk T, the said disk being keyed upon the end of the sleeve g, so that its rotation will 50 be transmitted by means of the coupling K to the shaft W, and consequently to the rope-pulleys secured to the same.

If the two wheels R and R' are driven simultaneously, as is the case when the roller 55 C rotates—*i. e.*, when roving is delivered—the disk T will rotate with a speed depending upon the difference of velocity of the wheels R and R', the wheel R' being larger than R and the pinion z larger than r. The 60 shaft W and the pulley S will consequently assume a certain speed, during which the carriage-rope runs on the large portion of the pulley S. If thereupon the roller C is stopped by the disengagement of the coupling K', the 65 wheel R' remains at rest and the disk T, together with the shaft W, immediately assumes a lower speed. About at the same

time the carriage-rope passes onto the spiral of the pulley S, the said pulley being keyed on the shaft W in the position requisite therefor. 70

In order to maintain the wheel R' with certainty at rest after the roller C has been disengaged from its driving-gear, a brake or other equivalent device may be applied to 75 either of the parts R' or C. In Figs. 3 and 4 an arrangement is represented in which a brake-pulley B is keyed on the shaft C' of the roller, the said pulley having a brake-strap 80 passing around it, which is connected with its respective ends to the fixed pin c and to the upper end of the lever e, pivoted to the pin c, so that when the lever e is turned in the direction of the arrow m, Fig. 4, the brake-strap is drawn tight and the shaft C' held 85 fast. The motion of the lever e is brought about by means of a wedge u, which is pushed between the lower end of the lever and a fixed abutment n. This wedge forms the 90 end of a rod t, movable lengthwise and connected to the lower end of the disengaging-lever h of the coupling K', the said lever being operated, as in the present machines, by a spring f and a rotating tappet E and maintained in its position subsequent to the action of the latter by a pawl i. If for the purpose of disconnecting the roller C the pawl i is raised by means of a counter, as usual, the spring f pulls the top end of the lever to the left, (relatively to the drawings,) so that at 95 the same time the coupling K' is disengaged the wedge u is moved to the right. If at the commencement of a new run-out of the carriage the coupling K' is re-engaged by the tappet E, the wedge u is retracted and the 100 roller C and wheel R' are released again.

In consequence of the reduction in size of the portion L and increase of the portion V of the run-out pulleys, these pulleys may be united with the counter-pulleys S' and keyed 105 on a shaft W, having a thickness proportionate to the strains to which it is exposed and passing through the pulleys, as shown by Fig. 3. This affords another advantage relatively to the parallel motion of the carriage. For 110 producing this parallelism of motion of the carriages of self-actors for spinning carded yarn various more or less complicated constructions have heretofore been employed, as, for the reasons stated, it is impossible to pass 115 a shaft of the requisite thickness through pulleys of the present proportions. The new pulleys being, however, adapted to have such shaft passed through them may be employed for guiding the carriage parallel, in like manner as the cylindrical run-out pulleys of self-actors for spinning cotton. For this purpose the run-out shaft W, driven at different speeds, as described, is arranged to extend from one 120 end of the machine to the other, as shown by 125 Figs. 5 and 6. Two, three, or more combined pulleys S S' are placed thereon, and all the pulleys S' are connected to the carriage directly by ropes s', while the pulleys S are con- 130

nected thereto by ropes s , passing over guide-rollers r' . The run-out shaft and the carriage-guiding shaft of the present self-actors are thus united into one, and the construction is 5 considerably simplified.

I claim as my invention—

1. In self-actors, the combination, with the shaft W , the run-out pulley S , fixed thereon and having two portions of different diameters, the roller C , the shaft C' , and the spur-wheels $Z Z'$, of the pinion z , fixed to the wheel Z , the disengaging-coupling K' , the parts whereof are connected, respectively, to the shaft C' and the wheel Z' , the pinion r , keyed 15 on the shaft C' , and a differential wheel-work gearing with the pinions z and r and connected to the shaft W , substantially as specified.

2. In self-actors, the combination, with the shaft W , the run-out pulley S , fixed thereon 20 and having two portions of different diameters, the roller C , the shaft C' , and the spur-wheels $Z Z'$, of the pinion z , fixed to the wheel Z , the disengaging-coupling K' , the parts whereof are connected, respectively, to the shaft C' and the wheel Z' , the pinion r , keyed 25

on the shaft C' , and a differential wheel-work comprising the sleeve g , connected to the shaft W , the loose spur-wheels R and R' , gearing with the respective pinions z and r and having the bevel-wheel teeth $k k'$, the disk T , keyed to 30 the sleeve g , and the bevel-wheel U , pivoted to the disk T and gearing with the teeth k and k' , substantially as set forth.

3. In self-actors, the combination of the shaft W , two or more pulleys $S S'$ fixed thereon, 35 each having two portions of different diameters, the roller C , the shaft C' , the spur-wheels $Z Z'$, the pinion z , the disengaging-coupling K' , the pinion r , a differential wheel-work 40 gearing with the pinions z and r and connected to the shaft W , ropes $s s'$, connecting the said pulleys with the carriage, and guide-rollers r' , substantially as described.

In testimony whereof I have hereunto set my hand in the presence of two subscribing 45 witnesses.

OSCAR SCHIMMEL.
